UNITED STATES PATENT OFFICE

2,484,933

METAL FILE CABINET

John Coyle and William F. Punte, Baltimore, Md.,
assignors to Continental Can Company, Inc.,
New York, N. Y., a corporation of New York

Application May 16, 1946, Serial No. 670,207

1 Claim. (Cl. 220—31)

1

The invention relates to new and useful improvements in metal file cabinets.

An object of the invention is to provide a metal file cabinet wherein the body portion is reinforced at the open end thereof and shaped so as to provide a cover rest and wherein the cover is hingedly connected to the reinforcement of the body.

A further object of the invention is to provide a cabinet of the above type wherein the reinforcing member is made of a separate piece of metal shaped to embrace the walls of the body and is preferably secured thereto by welding.

A further object of the invention is to provide a file cabinet of the above type wherein the reinforcing member is beaded and is provided with a rod inserted in the bead and encircling the open end of the body and wherein the cover is provided with extensions at intervals which encircle the rod, thus forming a hinge connection for the cover.

These and other objects will in part be obvious and will in part be hereinafter more fully disclosed.

In the drawings:

Figure 1 is a front view of the cabinet with the corner portions broken away to show the seam connecting the side members to the top and bottom of the cabinet;

Figure 2 is a view partly in side elevation and partly in vertical section from front to rear through the cabinet;

Figure 3 is a view showing a portion of the cabinet in vertical section with the cover partly open;

Figure 4 is a vertical section through the hinge connection between the cover and the body of the container; and

Figure 5 is a view in perspective showing the extensions on the cover which encircle the rod in the reinforcing member on the body.

The improved metal file cabinet includes a body portion having a flat front wall 1 and a flat back wall 2. Extending from front to back are flat side walls 3 and 4. Seamed to the lower end of the front, back and side walls of the cabinet is a bottom member 5 which is provided with downwardly projecting ribs 6, 6 serving as rests for the body of the cabinet. The upper ends of the side members 3 and 4 incline upwardly from front to rear of the cabinet. The front, back and side walls of the cabinet are all offset inwardly, thus providing a shoulder 7 which extends all the way around the upper end of the body portion.

Secured to and embracing the upper end of the body wall in the offset portion thereof is a re-

2

inforcing strip of metal 8. This reinforcing strip of metal is bent upon itself so as to provide an inner member 9 and an outer member 10. These members fit down over the upper edge portion of the wall and are secured thereto by spot welding, as indicated at 11. This reinforcing metal strip extends all the way around the open end of the body portion of the cabinet and the inner member 9 of the strip is notched at the corner in the usual way so that the outer member will form a continuous strip. The lower edge portion of the outer member 10 of the reinforcing strip is rolled into a hollow bead 12. This hollow bead rests on the shoulder 7. Disposed within the hollow bead is a rod 13 which encircles the open end of the cabinet and forms a further reinforcing member for the upper edge portion of the body.

The cover for the file cabinet includes a flat front wall 14, a flat rear wall 15 and side walls 16, 16. The lower edges of the side walls are similarly inclined to the upper edges of the side walls of the body. A top 17 is secured to the front, back and side walls by a seam.

The lower edge portion of the front, back and side walls of the cover are rolled inwardly to form a hollow bead 18. A rod 19 is disposed in this hollow bead and encircles the cover.

At the rear side at intervals the rear wall 15 is slit and provided with extensions 20, 20. These extensions are rolled as indicated at 21 so as to encircle the rod 13. The rod 13 thus becomes a pintle for these encircling members 21 and thus the cover is hinged to the body. The outer dimensions of the cover are similar to the outer dimensions of the body and the inwardly rolled bead on the cover will extend down over the reinforced inwardly offset portion of the body wall and rest on the bead 12 when the cover is in closed position.

The reinforcing strip together with the rod 13 encircled by the bead 12 form a very rigid reinforcement for the open end of the file cabinet. Likewise, the beaded lower edge portion of the cover, together with the rod disposed therein, serves as a very rigid reinforcement for the open end portion of the cover. When the cover is in closed position, it extends down over the reinforced inwardly offset portion of the body wall and this prevents dust and dirt from getting into the cabinet when closed.

While the reinforcing strip is described above as attached to the body and the cover subsequently hinged thereto, it will be understood that this reinforcing strip can be very readily secured

to the cover by attachment to the rod 13 and then slipped on over the upper portion of the body wall and welded thereto. This makes a very easy way of assembling the cover and body. As a means for holding the cover of the file cabinet in closed position, a nib is formed in the member 10 as indicated in dotted lines at 22. This nib will spring over the bead 18 on the cover and yieldingly hold the cover in closed position.

It is obvious that minor changes in the details of construction and shaping of the parts may be made without departing from the spirit of the invention as set forth in the appended claim.

We claim:

A metal file cabinet comprising a body having flat front, back and side walls, said side walls at their upper ends being inclined upwardly from front to back, said body walls being bent so as to extend inwardly and thence upwardly, a reinforcing metal strip bent upon itself and embracing the upwardly extending portion of the body walls all the way around the open end of the body, said strip being secured to the body as a unit, the outer member of the strip being rolled into a bead having a rod disposed therein and encircling the end, said bead contacting the inwardly bent part of the body wall so as to provide a strengthened open end, a cover similar in shape to said body and dimensioned so as to tele-

scope over the inset portion of the body wall, said cover having the lower edge thereof rolled inwardly into a bead adapted to rest when in closed position on the bead of the reinforcing strip attached to the body, said rear wall of the cover having integral extensions encircling the rod contained in the bead of the reinforcing strip at spaced intervals for hingedly connecting the cover to said body.
